SIDE SLIPPING WEFT DETECTOR FOR LOOMS

Filed July 30, 1926

Patented Dec. 18, 1928.

1,695,365

UNITED STATES PATENT OFFICE.

ALBERT CEDERLUND, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SIDE-SLIPPING WEFT DETECTOR FOR LOOMS.

Application filed July 30, 1926. Serial No. 125,853.

This invention relates to side slipping weft detectors for looms and it is the principal object of the invention to provide a very simple connection between the detector and the weft replenishing mechanism to the end that replenishment may be initiated with a minimum number of parts.

In Patent No. 1,668,393, issued May 1, 1928, to Blanchard there is shown a detector having both sliding and angular movements with respect to a fixed support, the sliding movement occurring when sufficient weft is present and the angular movement taking place when insufficient weft remains on the bobbin. There is shown in that application a regularly moving actuator lever the motion of which is interrupted at the time of indication of weft exhaustion by a controller operatively connected to the sliding and angularly moving detector wire. The connection shown therein requires an adjustment for each different position of the support longitudinally of the shuttle and it is an important object of my present invention to provide a controller so related to the actuator lever as to be properly positioned without further adjustment for a number of different positions of the detector support.

It is a further object of my present invention to provide a support formed preferably of sheet metal and having a relatively strong body to withstand the pressure of the actuating lever but being so light as not to interfere with the proper action of the detector.

With these and other objects in view which will appear as the description proceeds my invention resides in the combination and arrangement of parts hereinafter described and set forth in the claims.

In the accompanying drawings wherein I have shown a convenient embodiment of my invention,

Fig. 1 is a top plan view of a detector having my invention applied thereto, certain parts being in section and certain other parts being broken away for the sake of clearness,

Fig. 2 is a vertical section on line 2—2 of Fig. 1,

Figs. 3 and 4 are vertical sections on lines 3—3 and 4—4, respectively, of Fig. 1, and

Fig. 5 is a front elevation of the detector bed and the supporting structure for the same, looking in the direction of arrow A, Fig. 1.

Referring to the drawings it will be seen that I have shown a loom frame 10 having secured thereto the foot of a weft replenishing mechanism indicated at 11, said foot supporting a stud 12 on which is mounted for angular movement a transerrer arm 13 having depending fingers 14. The transerrer arm is provided with a heel 15 which engages a fresh bobbin to insert the same into shuttle S at the time of transfer.

A bracket 16 is secured to the loom frame and has slidably mounted therein a block 17 which receives a downward motion on every detecting beat of the loom, said block being pivotally connected to an actuator lever 18. The inner end of the lever is connected to a rod 19 which is attached operatively to the weft replenishing mechanism (not shown) preferably of the multi-color type and the outer end of the actuator lever extends to the right as indicated in Fig. 1. On each detecting beat of the loom the actuator lever is moved downwardly by the block 17 and so long as sufficient weft for continued weaving is present the outer end of lever 18 will be uninterrupted and free to descend but at weft exhaustion said outer end will be held in raised position by mechanism to be described, with the result that rod 19 will be depressed creating a condition which as set forth in Patent No. 1,030,748 corresponds to the initiation of weft replenishment.

The detector comprises a bed 20 mounted on the foot 21 and having adjustable connection with a stand 22 secured to the loom frame 10. This connection is indicated in Fig. 5 where bolts N pass through horizontal slots H in the stand 22 and vertical slots V in the foot 21. Said bed 20 has the upper part thereof recessed and surrounded for the most part by a wall 23. The rear part of the wall is broken away to provide a slot 24 through which extends a side slip weft detector 25 formed of wire the rear end of which is notched as at 26. The forward part of the detector 25 extends laterally as at 27 and the left hand end thereof is received in a notch formed with the left wall 23 and a lug 28 cast integrally therewith. A light tension spring 29 is attached to a crimped part of the lateral extension 27 and also a lug 30 cast on the bed 20, said spring holding the wire detector 25 in the normal position indicated in Fig. 1 by reason of the contact

of the lateral extension 27 with the lug 28 and the boss 31 cast integral with the bed 20.

Under normal conditions when there is sufficient weft for continued weaving on the bobbin B the teeth 26 will be embedded in the yarn on the forward movement of the lay and the detector 25 will be moved forwardly with a right line motion, but when insufficient yarn is present the teeth 26 will slide along the denuded bobbin, the wire 25 moving about the aforesaid notch as a center and the extension 27 moving away from the boss 31 because of the fact that the teeth 26 are offset from the notch. Adjustment of the detector bed 20 in the direction of the length of the bobbin may be obtained by loosening the bolts N and moving the foot 21 in a horizontal direction to the desired location. The matter thus far described is common to the devices set forth in the aforesaid patent to Blanchard.

In carrying out my improvements I provide a simple controller C for the actuator lever 18, said controller comprising upper and lower arms 40 and 41, respectively, separated to define a space 42. The upper arm is provided with a head 43 the lower portion of which slides on the top of a cap 44 secured by screws 45 to the bed 20, said head sliding under the extended right hand end 46 of the actuator lever 18.

The lower edge of the end 46 is inclined upwardly and to the left as shown in Fig. 4 so as to compensate for lateral adjustments of the detector bed. When the controller is relatively near the block 17 there is a little lost motion between said controller and the actuator, but when the controller is relatively far from the block there is practically no lost motion between the parts. The result of this is to produce the same throw on that end of the actuator connected to the rod 19 irrespective of the lateral position of the controller.

In order that the head 43 may be removed from under the actuator lever when sufficient weft is present I provide the lower arm 41 with a notch 47 which bridges the extension 27. The arm 41 is extended upwardly as at 48 to engage the under side of the cap 44 to steady the controller as the same moves. The forward wall 23 is provided with a narrow notch 49 which guides the lower arm 41 and the upper arm is guided by having the lower part of the head 43 passed between two spaced parallel forwardly extending lugs 50 cast on the cap or cover 44. By reason of the notch 49 and the lugs 50 the controller C will be guided with respect to the support for the detector wire 25 and the actuator lever. When the detector moves forwardly on non-indicating detecting beats the controller will be moved to the left from the position shown in Fig. 3 so that the actuator lever can descend without interruption, but when the

detector 25 swings angularly at the time of indication the controller C will remain practically at rest because of the fact that the notch 47 in the lower arm 41 is very close to the lug 28.

In order to provide for withdrawing the detector on transferring beats I provide one of the fingers 14 with a stud 51 which passes into the space 42 and engages the vertical forward portion of the controller C to move 75 the head 43 from under the actuator lever and the rear part of the detector wire 25 from the path of the incoming bobbin. The actuator lever 18 extends over the head 43 throughout a limited range of adjustment 80 of the support for the detector longitudinally of the shuttle.

From the foregoing it will be seen that I have provided a simple controller guided by and laterally movable with the support to 85 any position within a limited range of adjustment without disturbing the operative relation between the actuator lever and the controller head 43.

Having thus described my invention it will 90 be apparent that changes and modifications may be made therein by those skilled in the art without departing from the spirit and scope of the invention, and I do not wish to be limited to the details herein disclosed but 95 what I claim is:

1. In a weft detector for looms having a support and a detector movable longitudinally in the support when sufficient weft is present and movable angularly with respect to the support when insufficient weft is present, an actuator having a regular movement on detecting beats of the loom, a controller carried by the support and operatively connected to the detector to be moved by the latter in a 100 direction substantially parallel with the motion of the detector on non-indicating detecting beats of the loom and having a portion thereof normally operatively related to the actuator, said actuator having a portion 110 extending laterally on both sides of the cooperating part of the controller, and means to vary the position of the support and the detector, the controller and actuator maintaining operative relationship throughout a limited range of adjustment of the support.

2. In a weft detector for looms having a support and a detector movable longitudinally in the support when sufficient weft is present and movable angularly with respect to the support when insufficient weft is present, an actuator lever movable in a fixed path and having an operative movement on detecting beats of the loom, a controller guided for movement in a fixed plane with respect to 120 the support, operative connections between the controller and the detector to give the controller a movement on non-indicating detecting beats of the loom, and means to vary the position of the detector and support 125 130

- lengthwise of the actuator, said actuator having a portion normally extending on both sides of the controller and being operatively related with the latter throughout a limited
- 5 range of adjustment of the support, the controller carried by the support and maintaining the same relative position with respect to the support for all adjusted positions of the said support.
- 10 3. In a weft detector for looms having a support and a detector movable longitudinally in the support when sufficient weft is present and movable angularly with respect to the support when insufficient weft is present,
- 15 an actuator lever movable in a fixed path and having an operative movement on detecting beats of the loom, a controller operatively connected to the detector and having a portion thereof normally lying in the path of the
- 20 actuator, means to move the support longitudinally with respect to the actuator, and fixed guides on the support between which the controller is movable under influence of the detector, said guides maintaining the
- 25 same relative position normally between the

controller and the support, and the actuator being operatively related with respect to the controller for various adjusted positions of the support longitudinally of the actuator.

4. In a weft detector for looms having a support and a detector movable longitudinally in the support when sufficient weft is present and movable angularly with respect to the support when insufficient weft is present, an actuator moving in a fixed path and having an operative movement on detecting beats of the loom, a controller operatively connected to the detector and having a portion thereof normally lying in the path of the actuator, said controller being formed of a flat member having spaced arms one of which is formed with a head lying under the actuator and the other arm being notched to receive a portion of the detector wire, and upstanding spaced guides on the support between which the controller slides.

In testimony whereof I have hereunto affixed my signature.

ALBERT CEDERLUND.
